BOX FOR SEWING MACHINE ATTACHMENTS OR THE LIKE

Joseph G. Rakacs, Toms River, N.J., assignor to The Singer Company, New York, N.Y.

Filed Apr. 26, 1973, Ser. No. 354,410

Term of patent 14 years

Int. Cl. D9—03

U.S. Cl. D9—234

Fig. 1

Fig. 2

FIG. 1 is a front perspective view of a box for sewing machine attachments or the like showing my new design, and

FIG. 2 is a rear perspective view thereof.

The bottom is substantially plain and unornamented.

I claim:

The ornamental design for a box for sewing machine attachments or the like, substantially as shown and described.
